TAPE HOLDER

Herbert Weston, New York, and Romeo T. Proulx, Copiague, N.Y., assignors to Visirecord, Inc., New York, N.Y., a corporation of New York

Application May 13, 1957, Serial No. 658,875

5 Claims. (Cl. 211—60)

This invention relates to tape holders and more particularly to a holder which may be placed in a filing tray and support a number of punched tapes.

The use of punched tapes containing data of various kinds is steadily increasing in connection with various fields of business and various types of records. It is not only necessary to provide suitable means for filling such tapes, but also to index them or otherwise simplify the location of a desired tape when it is wanted. In fact, the filing of such tapes and location of desired tapes when wanted has developed into one of the most expensive and time-consuming chores of offices in which such tapes are used.

In the present invention I provide a holder for such tapes in the flat-folded form now in extensive use, and suitable indexing means whereby a tape may be readily located when desired and easily returned to its proper place. With the greater length tapes now being used, a flat pocket on a registry card or the like does not suffice for holding such tapes. I, therefore, provide sleeves which are removably mounted on a card or support, and which have a depth sufficient to receive flat folded tapes of several thicknesses. Thus, with sleeves of a depth of $1\frac{1}{32}$ " a seven channel tape folded to $8\frac{1}{2}$ " packs of lengths up to 54 feet can be placed in a sleeve.

The sleeves are of a width to conveniently receive the tapes and a number of such sleeves can be supported on a single panel. By providing suitable indexing means on the upper edge of the panel in alignment with each sleeve, the desired tape can be quickly located, and quickly returned to its proper place when desired.

In the accompanying drawing, I have shown one form of the invention. In this showing:

Fig. 1 is a front elevation, parts being shown in section; Fig. 2 is an enlarged, vertical, sectional view on line 2—2 of Fig. 1;

Fig. 3 is a similar view on line 3—3 of Fig. 1; and Fig. 4 is an enlarged, horizontal, sectional view on line 4—4 of Fig. 1.

In carrying out the invention, I provide a panel 2 which may be formed of thin sheet metal or other suitable material. The panel is of proper height and width to be received in a filing tray, the drawer of a filing cabinet or the like, and is preferably provided with suitable end members 4. The end members are of greater thickness than the sheet of which the panel is formed and extend below the lower edge of the panel, as shown in Fig. 1. The side edges of the panel are secured to the end members in any suitable manner. As shown in Fig. 4, the end members may be provided with slots in which the edges of the panel are received. The edges are retained in the slots by suitable means, such as staples 6.

The lower edge of the panel is shaped to form a pocket 9 to receive the lower ends of the sleeves in which the tapes are kept. As shown, a portion 8 near the lower edge is arranged at right angles to the body portion 2 of the panel and the edge portion 10 is then extended up-

2

wardly, parallel to the body portion 2 and spaced from it a distance slightly greater than the depth of the sleeves.

Adjacent the upper edge of the body of the panel, a strip 12 is secured to it by eyelet rivets 14 or other suitable means. The lower edge of this strip is offset and spaced a slight distance from the panel, as indicated at 16 (see Fig. 2). Beyond the strip 12, the body 2 of the panel extends upwardly and rearwardly as at 18, and then forwardly and downwardly as at 20, the edge portion 20 being spaced from and substantially parallel to the adjacent portion 18.

A transparent, plastic index card holder 22 of U-shaped cross section is arranged over the edge of the portion 20 of the panel. One leg of the plastic holder is thus arranged between the sections 18 and 20 to secure the holder in position.

The sleeves 24 which receive the tapes are made of any suitable material. I preferably make them of a transparent, plastic, such as Tenite II, a product of the Tennessee-Eastman Company. They may be rectangular in shape consisting of front and rear walls 26 and 28 spaced a desired distance from each other by end walls 30. At the upper end, the front wall 26 is rounded downwardly as at 34, and the rear wall extends above the upper edges 25 of the end walls 30, as indicated at 36 in Fig. 2.

The vertical spacing between the upper edge of wall 10 and the offset portion 16 of strip 12 is less than the height of the sleeve, and means are arranged in the pocket to urge the sleeves upwardly to retain the edge 36 of 30 the rear wall of the sleeve under the offset portion 16, as shown in Fig. 2. The latter means in this preferred embodiment is a resiliently supported false bottom which is formed by placing a strip of sponge rubber 38 in the bottom of the pocket. A yielding bottom member 40 35 overlays and is supported by the sponge rubber. The bottom member may consist of a strip of metal having end portions 42 turned downwardly and under the bottom 8 of the pocket to prevent its displacement.

Thus when a sleeve is to be inserted or removed, the 40 strip 38 is compressed by forcing the sleeve downwardly until rear edge portion 36 clears the offset portion 16 of the strip. The rounded portion 34 at the top of the sleeve facilitates removal of the sleeve from the panel, or removal of the tape from the sleeve.

One of the problems in the use of such tapes is the 45 indexing of the tapes so that a desired one may be quickly located. In the panel of the present invention, the index 50 cards 44 of substantially the same size as the width of the sleeves may be arranged between the index holder and the edge portion 20 of the panel. They may be aligned with the respective sleeves laterally of the panel. Thus the desired sleeve may be located by glancing at the row 55 of index cards, and the proper one removed. If the tapes are to be located by indexing laterally arranged on the panel with the proper index member in alignment with each tape, it is essential that the sleeves and index cards be kept in proper alignment. In some offices it is 60 the practice to remove a tape from the sleeve and leave the sleeve in position on the panel. In such cases, the rear wall 28 of the panel may be provided with suitable printed matter such as the words "Tape Out," as indicated at 46 in Fig. 1. The walls of the sleeve being transparent, such wording will be visible when the tape is 65 removed from a sleeve. This will indicate that the empty sleeve is not to be removed.

In some instances it is the practice to remove the sleeve and tape. This presents a greater possibility of misplacing a number of sleeves. Thus, assuming a panel 70 supporting five sleeves at the left, as in Fig. 1, with the proper indexing above each sleeve, if we assume removal

of the third sleeve, there is then a tendency to move the fourth and fifth sleeves to the positions initially occupied by the third and fourth. This would not only eliminate a place for replacement, but it would align improper indexing with the sleeves then in the third and fourth positions. Where the sleeve is removed with the tape the indication such as "Tape Out" may be placed on the face of the panel in the position occupied by each tape. Then in the example given with the third sleeve of Fig. 1, the words "Tape Out" would tell that the fourth and fifth sleeves are not to be moved toward the left and thus place them out of alignment with their index cards.

In some instances the panels may be filed alone. That is true where the indexing information necessary to locate a desired tape is simple, such as a series of numbers, as indicated in Fig. 1. In some instances it may be desirable to have more information with respect to a given tape, or information relating to the same subject as that which is on the tape may be placed on cards. In such instances banks of cards may be arranged behind the panels, the panels thus serving the function of a divider in addition to that of a tape holder. Such cards may be correlated to the tapes by the index matter, such as the numbers on the index cards of Fig. 1.

I claim:

1. Apparatus for filing tapes, containing recorded data including a panel member to be received in a filing cabinet or drawer, said panel comprising a sheet of material of a suitable width to be received in the drawer, and end members secured to the opposite side edges of said sheet, the improvement which consists of a pocket formed on the lower edge of the sheet, a strip secured to the sheet near its upper edge, the lower edge of the strip being spaced from the sheet, and sleeves to contain the tapes, the bottom portions of the sleeves being received in the

25

30

4

pocket, the sleeves having rear walls extending upwardly beyond the rest of the sleeve and being received between said sheet and the spaced portion of said strip to hold the sleeves in place.

5. 2. A device in accordance with claim 1 in which the pocket is provided with a false bottom to permit a sleeve to be forced downwardly in the pocket to release its upper edge from the strip.

10 3. A device in accordance with claim 1 in which a layer of elastic material is arranged in the pocket to normally urge the sleeves upwardly and retain the upper edges of the sleeves in position behind the strip.

15 4. Apparatus in accordance with claim 1 in which the lower edge of the sheet is extended outwardly from the sheet, and then parallel to the sheet to form said pocket.

5. A device in accordance with claim 1 in which the sheet is extended upwardly and rearwardly beyond the point where the strip is mounted, the upper edge then extended downwardly and forwardly parallel to the upwardly and rearwardly extending portion, and a transparent, U-shaped index member is mounted on said upper edge of said sheet.
